United States Patent Office

Des. 186,262
Patented Oct. 6, 1959

186,262

APRON

Dale L. Hill, Storm Lake, Iowa

Application February 17, 1958, Serial No. 49,657

Term of patent 14 years

(Cl. D3—26)

The drawing shows a front elevational view of an apron showing my new design.

I claim:

The ornamental design for an apron, as shown.
